INSTRUMENT FOR USE IN OBTAINING
STROBOSCOPIC EFFECTSRichard Maxwell Eaton, Niagara Falls, N. Y., as-
signor to Niagara Searchlight Co. Inc., Niagara
Falls, N. Y.

Application July 24, 1935, Serial No. 32,932

3 Claims. (Cl. 176—124)

This invention relates to improvements in producing stroboscopic effects, such for example as are employed in instruments for use in determining synchronism of two members.

5 It has been found that in certain types of apparatus operating on the stroboscopic principle, the effects vary considerably. For example, in determining whether the ignition of an internal combustion engine is in properly timed relation to 10 the rotation of the engine, a flashing light actuated by electric impulses supplied to a spark plug has been projected on a white mark on a fly wheel or other rotating part of an engine. With instruments of this type as heretofore used, difficulty has, however, been encountered due to the 15 fact that the duration of the light was at times so long as to make the mark on the fly wheel or rotating part visible over too great an arc of movement of the rotating part. Furthermore, the 20 stroboscopic effect thus produced by the same instrument or apparatus varied on different engines.

The objects of this invention are to control the duration of the light in a stroboscopic device in such a manner as to render a mark on a revolving 25 member visible only through a very small arc of its movement; also to control the duration of the light by controlling the current delivered to the light source; also to provide an instrument of this kind with an adjusting spark gap controlling the 30 duration of light; also to improve methods and instruments of this kind in other respects hereinafter specified.

In the accompanying drawing:

Fig. 1 is a longitudinal central sectional elevation 35 of an instrument for producing light flashes and provided with means embodying this invention for varying the duration of the flashes.

Fig. 2 is a fragmentary sectional elevation thereof on an enlarged scale, showing the adjusting 40 means associated with the instrument.

Fig. 3 is a transverse sectional elevation on line 3—3, Fig. 1.

In instruments of this kind, the light source is generally in the form of a gas filled tube which 45 is so constructed as to be illuminated by electrical impulses. A tube of this kind may be incorporated in any suitable type of apparatus or appliance and the construction illustrated by way of example, shows the tube applied to a portable 50 instrument. The instrument shown includes a body tube 5 having an outwardly flaring shell 6 secured to one end thereof within which a reflector 7 is arranged. This reflector in the construction illustrated bears against a glass disk or 55 lens 8 held on the shell 6 by means of a bezel ring 9.

The inner end of the reflector 7 is provided with an opening through which a light source, such as a glow tube 10, may extend into the reflector so 60 that light will be projected in the form of a beam

through the lens or glass plate 8. The ends of the glow tube 10 may be suitably secured in a cylindrical base portion 11, the ends of the glow tube extending into one end of the base 11 and being connected to suitable conductors 13 shown 5 in broken lines in Fig. 1, which terminate in the other end of the base. This base is preferably secured within a cylinder 12 of insulating material arranged within the tubular body 5. The base 11 may be provided with laterally projecting pins or 10 studs 15 arranged to enter into bayonet slots 16 in the insulating cylinder 12 or the base may be otherwise removably secured within the instrument. The inner end of the base portion 11 is 15 provided with suitable terminals of the conductors 13, which engage with terminals 16 and 17 yieldingly pressed outwardly by means of springs 18 and 19 to insure adequate contact through which electric current may be carried to the body portion 11 of the tube 10. The springs and movable 20 contacts 16 and 17 are suitably arranged in an insulating member or part 20 secured within the tubular body 5 of the instrument in any suitable manner, for example, by securing the insulating member 20 to the insulating tube 12. 25

At the other end of the tubular body member 5, a ferrule or cap 24 is secured which has an inwardly extending flange engaging an insulating bushing 25 which, in the construction shown, in turn engages the end of the insulating cylinder 12. 30 This bushing is provided with apertures through which suitable conductors 26 and 27 extend through which electric impulses may be transmitted to the gas-filled tube 10. The conductor 26, for example, engages at its outer end with 35 another movable contact point 28 also arranged in the insulating member 20 and urged into contact with the conductor 26 by means of the spring 18. All of the parts thus far described have heretofore been used in connection with instruments 40 of this kind and of themselves do not constitute a part of this invention, being shown and described merely to illustrate by way of example, a device to which my invention may be applied.

I have found that when instruments of this 45 kind are used in connection with the ignition systems of various types of internal combustion engines, the stroboscopic effects produced are not always sufficiently clear to facilitate the proper timing of an engine, since with some types 50 of machines, the light colored mark formed on the fly wheel or other part geared thereto is visible over such a large arc of movement of the rotatable part as to make it difficult or impossible to determine the correct timing of the engine. 55 This is due to the fact that the light from the glow tube is too long in duration and this duration varies with different engines due to different electro-magnetic characteristics of the ignition system. 60

In accordance with my invention, I provide means whereby the duration of the light of the glow tube may be varied in such a manner that the mark on a revolving part of the engine will be visible only through a very small arc of its movement. This I accomplish by providing means for varying the amount of current supplied to the glow tube. Any suitable or desired means for accomplishing this result may be used. 5
 10 In the particular construction illustrated, I provide an adjustable spark gap in the current leading to the glow tube, which may, for example, be effected by adjusting one or both of the conductors leading to the instrument toward and 15 from fixed current conducting parts within the instrument. As shown in the drawing, I provide an adjustable spark gap between the end of the conductor 27 and a stationary conductor 30 secured in the insulating member 20 and in contact with the spring 19. For this purpose, I provide a sleeve 31 through which the cable 27 extends and to which the outer portion of the cable is secured. This sleeve 31 in turn may be adjustably mounted on the instrument in any suitable manner. In the construction shown, the insulating bushing 25 is provided with an aperture within which the sleeve 31 may be moved lengthwise against the frictional contact of the bushing 25 with the sleeve 31. If desired, the bushing 25 may be provided with a hub or extension 32 which will afford a more extended frictional bearing for the sleeve 31.

A variation of the spark gap or distance between the end of the cable 27 and the conductor 30 is effected by adjusting the sleeve 31 in and out with reference to the bushing 25. The correct position of the sleeve 31 produces a clear view of the mark on the revolving part, since the mark on the revolving part may then be seen only in a small arc of movement of the revolving part.

This correct position can be readily determined by first observing the mark on the revolving part. If this mark is in the form of a radial line made by chalk or light colored paint, then if the line appears in the form of a wide band, the spark gap is increased by adjusting the sleeve 31 and conductor 27 secured thereto outwardly. This adjustment is continued until the line is visible in the form of a narrow band. 15
 20 If this band is not in registration with the indicating mark on a stationary part near the revolving part, then the timing mechanism of the engine is adjusted to advance or retard the spark until the line or band is opposite the stationary indicating mark. If the line on the revolving part appears too faint or dim, the sleeve 31 is moved inwardly to reduce the spark gap.

25 It will, of course, be understood that any other means may be used for controlling the amount of current passing to the gas in the tube 10, the adjustable spark gap being merely illustrative of one embodiment of this invention.

30 I claim as my invention:
 1. In an instrument for use in synchronizing two parts by means of effects obtained by electric light flashes, the combination of a body tube, a block of insulating material fixed in said body tube, a gas-filled glow device mounted upon said body tube at one end of said block, a pair of

conductors mounted in and extending through said block and having electrical contact at one end thereof with the terminals of said glow device, a bushing of insulated material detachably secured at the other end of said body tube, a pair of insulated wires mounted upon said bushing with their ends extending into said body tube and effective to conduct electrical impulses to said conductors, and one of said wires being adjustable relatively to said bushing to form a 5 variable spark gap between said wire and one of said conductors to vary the duration of light flashes produced by said glow device.

2. In an instrument for use in synchronizing two parts by means of effects obtained by electric light flashes, the combination of a body tube, a block of insulating material fixed in said body tube, a gas-filled glow device mounted upon said body tube at one end of said block, a pair of conductors mounted in and extending through 10 said block and having electrical contact at one end thereof with the terminals of said glow device, a bushing of insulated material engaging the other end of said body tube, a cap detachably connected to said body tube and engaging said bushing for releasably securing it upon said body tube, a pair of insulated electric wires having their ends extending through holes in said bushing into said body tube and one of which is in relatively fixed relation to said bushing and engages one of said conductors and the other of said wires being movable endwise and being frictionally mounted in the hole in said bushing whereby its end may be adjusted toward and from the other conductor and retained in adjusted position to form a variable spark gap between said wire and said conductor to vary the duration of light flashes produced by said glow device.

3. In an instrument for use in synchronizing two parts by means of effects obtained by electric light flashes, the combination of a metallic body tube, a hollow lining member of insulated material extending substantially from end to end of and within said body tube, a block of insulating material in said body tube and fixed to said lining member, a gas filled glow device mounted upon said body tube at one end of said block, a pair of conductors mounted in and extending through said block and having electrical contact 15 at one end thereof with the terminals of said glow device, a bushing of insulating material secured at the other end of said body tube and engaging the adjacent end of said lining member, a pair of electric wires, one of which extends 20 through said bushing and contacts with one of said conductors, and the other electric wire being extended through a sleeve of somewhat yielding material which extends through and frictionally engages in a hole in said bushing and in turn 25 frictionally holds said wire with its end extending into said body tube, whereby said sleeve and the wire extending therethrough may be adjusted relatively to each other and relatively to said bushing and maintained in adjusted position by friction so that a variable spark gap may be formed between the end of said wire and said other conductor to vary the duration of light 30 flashes produced by said glow device.
